CLAIM

We claim the ornamental design for a fastener with anti-rotation device, as shown and described.

DESCRIPTION

FIG. 1 is an isometric view of a fastener with anti-rotation device.

FIG. 2 is a front view of the fastener with anti-rotation device of FIG. 1.

FIG. 3 is a rear view of the fastener with anti-rotation device of FIG. 1.

FIG. 4 is a left view of the fastener with anti-rotation device of FIG. 1.

FIG. 5 is a right view of the fastener with anti-rotation device of FIG. 1.

FIG. 6 is an enlarged top view of the fastener with anti-rotation device of FIG. 1.

FIG. 7 is an enlarged bottom view of the fastener with anti-rotation device of FIG. 1; and,

FIG. 8 is an exploded isometric view of the fastener with anti-rotation device of FIG. 1.

The broken lines in the drawings illustrate portions of the fastener with anti-rotation device and form no part of the claimed design.
